HEAT EXCHANGE DEVICE

Original Filed Oct. 6, 1927 2 Sheets-Sheet 2

UNITED STATES PATENT OFFICE

CLARENCE E. SAFFORD, OF CLEVELAND, OHIO

HEAT EXCHANGE DEVICE

Application filed October 6, 1927, Serial No. 324,342. Renewed August 25, 1931.

This invention relates to heat exchange devices and more particularly to apparatus for heating or cooling buildings, enclosures and the like through indirect action by the circulation of fluids through said devices.

One of the objects of the invention is the provision of new and improved heat exchange device that will have the maximum heat radiating or absorbing surface for the space occupied by the device.

A further object of the invention is the provision of a new and improved device that is not injured by freezing, has no pockets for collecting and retarding the flow of the circulating fluid, and wherein the circulating fluid, when the device is installed, may flow freely through the device, thus effecting a rapid interchange of heat and avoiding rusting or corrosion of the material of which the device is composed.

Other objects of the invention are the provision of a new and improved heat exchange device formed from sheet metal that is cheap to manufacture, easily assembled, rugged in construction, of light weight, that may be readily installed with a minimum amount of labor and expense, that may be assembled without stretching or otherwise injuriously distorting the metal, and that when installed will permit a rapid interchange of heat.

Other and further objects and advantages of the invention will appear from the following description taken in connection with the accompanying drawings, in which

- 35 Fig. 1 is a side elevation of the device;
- Fig. 2 is an end elevation thereof;
- Fig. 3 is a plan view, with parts in section and parts broken away;
- Fig. 4 is a vertical section on the line 4—4 of Fig. 1, with parts broken away;
- 40 Fig. 5 is a section on line 5—5 of Fig. 1, with parts broken away;
- Fig. 6 is a perspective view of a portion of the upper end and one side of the device;
- 45 Fig. 7 is a perspective view of a portion of one of the halves of the device;
- Fig. 8 is a plan view of a portion of one of the blanks, showing the notch therein; and
- Fig. 9 is a vertical section, similar to Fig. 4, 50 but showing a modified form of construction.

In the form of the device selected to illustrate one embodiment of the invention, and which is by way of example only, the device comprises the two halves or sides 10 and 11 formed from strips of sheet metal.

In the manufacture of sheet metal heat exchange devices, such as radiators, it has been the practice heretofore to stretch the metal at the ends in order to bring the adjacent edges together to form the folds or sections 60 of the device. In the construction of the present device, the stretching of the material is avoided by cutting substantially V-shaped notches 12, see Fig. 8, in the opposite side edges of the strip and then bending or corrugating the sheet to form the folds or corrugations 15 and the return curved portions 16 between the folds, after which the upper and lower ends of the return curved portions 16 are each pressed outwardly or flattened as at 17, see Fig. 7 to form a straight continuous surface. The slots 12 extend the full depth of the corrugation and its edges 13 and 14 are convex so that when the device is complete there will be no pockets for retaining water that would cause rusting of the material.

The dimensions and form of the slot 12 are such that when the ends of the return curved portion 16 of the corrugated sheet 80 are pressed outwardly, or flattened as at 17 to form a continuous flange as shown in Fig. 7, the edges 13 and 14 engage each other and are then secured together as by welding, thus forming what for convenience will be termed 85 one half of the radiator. The two halves are preferably duplicates, the other half being made in the same manner.

The two halves are connected together at their upper and lower ends by trough-shaped strips 18 and 20 respectively. Each of these strips is provided with straight flanges 19 which may be rabbeted as at 21 for receiving the flanges 17, see Fig. 4. The flanges 17 and 19 are secured together, as by welding.

The ends of the two halves are secured together in any suitable manner. The ends of the strips may be extended and connected directly together as by welding, but preferably, connecting strips 22 and 23 are employed for 100

this purpose. These strips, as well as the trough-shaped strips 18 and 20, may be made of heavier material for giving rigidity to the structure, and for constituting conduits 5 for draining the water where steam is employed as the heating fluid.

Each of the connecting strips 22 and 23 is provided with inwardly extending flanges 24 to which the edges of the sheet metal 10 forming the two halves of the device is secured as by welding. By means of this arrangement the device may be installed with either end or side turned upward. If mounted on end, the strips 22 and 23 will 15 form conduits for the water of condensation.

The strips 18, 20, 22 and 23 are preferably of heavier material than the corrugated sheet metal sides and may be stamped or otherwise formed. The ends of the strips 18, 20, 20 22 and 23 are formed into a circular projection 25 on which is rigidly connected the coupling 26 as by welding. The couplings 26 are internally threaded for receiving the pipe connection in the usual manner.

25 In order to increase the radiating or absorbing surface of the heat exchange device, the sides 27 and 28 of the corrugations 15 are parallel and the return curve 16 is on a comparatively large radius. This arrangement 30 will not only add to the radiating surface of the device, but will also permit a slight expansion of the same, should water freeze therein.

Suitable means are provided for preventing 35 collapse or unnecessary lateral and longitudinal expansion of the sheet metal corrugated structure. As shown, interlocking members are employed for this purpose. These members comprise Z-bars 29 and 31 which are 40 welded or otherwise secured to the return-curve 16 on the inner sides thereof. The bar 29 has its upper flange 32 secured to each of the return-bends 16 and is provided with an offset 33 in which the free end 34 of the Z-bar 45 31 is adapted to engage. The bar 31 in turn is provided with an offset portion 35 for receiving the free edge 360 of the bar 29.

In assembling the parts, the bars are first attached to the two halves of the radiator, the 50 halves are then assembled, after which the strips 18, 20, 22 and 23 are applied.

With the device in the position shown in Fig. 4 it will be observed that the bars 29 and 31 are so interlocked that they do not form 55 pockets for collecting water. The bar 29 overlaps the bar 31 thereby directing the water into the folds of the radiator. The ends of the bars extend through the strips 22 and 23 and are firmly secured therein in 60 any suitable manner as by being welded. Any suitable number of these reinforcing bars may be used. In the form shown, two pairs are employed between the upper and lower portions of the radiator.

65 In the construction of large radiators,

wherein the corrugations or folds are deep, it is desirable to provide reinforcing means between the corrugations. These reinforcing members may each comprise a channel bar 70 36 having the flanges 37 and 38 turned inwardly and secured to the adjacent sides of the corrugations in any suitable manner as by welding. These channel bars may extend substantially the entire length of the corrugations. In heat exchange devices, such as 75 the conventional radiators, these reinforcing members are not necessary, and may be omitted.

In Fig. 9 is shown a modified form of construction in which one of the side members 80 is omitted. This construction differs from that shown in Fig. 4 in that a sheet metal plate 100 is substituted for the side member 10. The construction is otherwise substantially the same. This arrangement is convenient for wall radiators and the like, making it possible to readily attach the devices to the walls of buildings and the like.

The sides 27 and 28 of the folds or corrugations 10 of the side members may be spaced 90 at any desired distance apart. The radiating surface for any given capacity of radiator will obviously be increased by decreasing the distance between the sides or folds of the corrugations, and the distance between the 95 corrugations.

A radiator or heat exchange device made in accordance with the disclosure herein is very light in construction and occupies a 100 minimum amount of space with a maximum amount of radiating surface. The device being made principally from sheet metal, the fabrication is largely a stamping and welding operation, and consequently the same can be manufactured at a fraction of the cost 105 necessary to produce the cast radiators that are in common use.

It is thought from the foregoing taken in connection with the accompanying drawings 110 that the construction and operation of my device will be apparent to those skilled in the art, and that various changes in size, shape, proportion and details of construction may be made without departing from the spirit and scope of the appended claims.

115 I claim as my invention:

1. In a heat exchange apparatus, the combination of a pair of sides folded, bent and welded to produce corrugations having substantially parallel sides and having closed ends, said sides terminating at the ends of the corrugations in spaced flanges, each flange constituting a continuous welding band extending throughout the length of the radiator, trough-shaped strips bridging the 120 spaces between said flanges and rigidly connected thereto, and cylindrical coupling members connected to the metal constituting said sides at the ends of said strips, said strips extending into said coupling members. 125 130

2. In a heat exchange apparatus, the combination of a pair of sheet metal sides bent into a succession of folds connected together by curved portions, means for connecting the 5 ends of said sides together permanently, and with the edges of the metal between the folds bent to constitute continuous flanges, the flanges at adjacent ends of the two sheets being spaced apart, and trough-shaped strips 10 attached to and bridging the spaces between said flanges, said trough-shaped strips opening toward each other.
3. In a heat exchange apparatus, the combination of a pair of sheet metal sides bent 15 into a succession of folds and with the ends of the folds brought and permanently fastened together, and with the edges of the metal between the folds constituting continuous flanges, the flanges at adjacent ends of the 20 two sheets being spaced apart, and strips attached to and bridging the spaces between said flanges, means for connecting the lateral edges of the sheets together and coupling members attached to the structure at the ends 25 of said strips, the metal of said means and strips being formed to constitute flanges to which are attached said coupling members.
4. In a heat exchange apparatus, the combination of a pair of sides folded, bent and 30 welded to produce parallel corrugations having closed ends, the ends of the inner portions of the corrugations being flattened and curved outwardly until they constitute parallel flanges, trough-shaped strips bridging the 35 spaces between the flanges and attached thereto and means connecting across between said inner portions of the corrugations between the ends thereof, to stiffen the structure.
5. In a heat exchange apparatus, the combination of a pair of sides folded, bent and 40 welded to produce parallel corrugations being substantially semi-cylindrical between their ends, the ends of said inner portions of the corrugations being bent outwardly until 45 they constitute parallel flanges at the closed ends of said corrugations, the length of the end edges of the sides remaining the same, and trough-shaped strips united to and bridging the spaces between the flanges.
6. In a heat exchange apparatus, the combination of a pair of sides folded, bent and 50 welded to produce parallel corrugations being substantially semi-cylindrical between their ends, the ends of said inner portions of 55 the corrugations being bent outwardly until they constitute parallel flanges at the closed ends of said corrugations, the length of the end edges of the sides remaining the same, and trough-shaped strips opening toward 60 each other and united to and bridging the spaces between the flanges, the side edges of the sheets being united and bent to form troughs which extend between the ends of 65 said trough-shaped strips, and coupling mem- bers united to said sides at the meeting points of said troughs.
7. In a heat exchange apparatus, the combination of a pair of sides folded, bent and 70 welded to produce corrugations connected together by curved portions and having closed ends, trough-shaped members opening toward each other and bridging the separated portions of said corrugations, and cylindrical coupling members connected with the metal 75 constituting said sides at the ends of said strips.
8. In a heat exchange apparatus, the combination of a pair of sheet metal sides formed 80 to produce corrugations having closed ends, trough shaped members bridging separated portions of said corrugations trough-shaped members connecting the side edges of said sheet metal sides, coupling members connected to the ends of said trough shaped members and means connecting across between the sheet metal sides intermediate the ends thereof and connecting to the adjacent bottoms of the corrugations and comprising bars having 85 inter-engaging portions.
9. In a heat exchange apparatus, the combination of a pair of sheet metal sides bent 90 into a succession of folds and with the ends of the latter brought and permanently fastened together, members bridging the spaces 95 between the folds, and members for connecting the lateral edges of the sheets together, said members being attached to each other and formed to constitute the inlet and outlet openings adjacent to the ends of said strips.
10. In a heat exchange device a pair of side members, each comprising a sheet of corrugated sheet metal, the sides of each corrugation being substantially parallel and connected to the adjacent corrugation by a return 100 curved portion, and means including rigid trough-shaped members opening towards each other for connecting the ends and edges of the side members.
11. In a heat exchange device, a pair of 105 corrugated sheet metal side members, said corrugations being curved at their outer portions and having their connecting portions curved, rigid trough-shaped members for connecting the upper and lower portions of said side members, and rigid trough-shaped members for connecting the ends of said side members together.
12. In a heat exchange device, a pair of 110 complementary corrugated sheet metal side members, said corrugations being curved at their outer portions and having their connecting portions curved, means for connecting the ends and sides of said members together, and reinforcing members secured to 115 the connecting portions of said corrugations and to the connecting means at the ends of said device, said reinforcing members being interlocked.
13. In a heat exchange device, a pair of 120
- 130

corrugated sheet metal side members, said corrugations being curved at their outer portions and having their connecting portions curved, rigid trough-shaped members for connecting the upper and lower portions of said side members, and a vertically extending reinforcing bar between said corrugations on the exterior thereof.

14. In a heat exchange device, a pair of corrugated sheet metal sides, the sides of said corrugations being parallel and connected together with curved portions, trough-shaped members opening toward each other connecting the sides and ends of said members, said members connected together at their ends and being extended laterally to form tubular projections, and coupler members rigidly secured on said projections.

15. In a heat exchange apparatus, the combination of a pair of sheet metal sides bent into a succession of folds and with the sides of each fold permanently connected together at the ends of the fold, the connecting portions of said folds being curved, and members for permanently connecting the edges of said sheet metal sides together.

In testimony whereof I herewith affix my signature.

CLARENCE E. SAFFORD.
